UNITED STATES PATENT OFFICE.

ARCHIBALD B. HEATH, OF LYNBROOK, NEW YORK.

DESIGN FOR A LAMP SHADE.

Application filed July 22, 1924. Serial No. 10,214. Term of patent 14 years.

To all whom it may concern:

Be it known that I, ARCHIBALD B. HEATH, a citizen of the United States, residing at Lynbrook, in the county of Nassau and State of New York, have invented a new, original, and ornamental Design for Lamp Shades, of which the following is a specification, reference being had to the accompanying drawing, forming part thereof.

I claim:

The ornamental design for a lamp shade, as shown.

ARCHIBALD B. HEATH.
